UNITED STATES PATENT OFFICE.

HARRY JOSEPH HICK, OF ALLIANCE, OHIO, ASSIGNOR TO THE MCCASKEY REGISTER COMPANY, (INCORPORATED IN 1914,) OF ALLIANCE, OHIO, A CORPORATION OF OHIO.

FILING APPLIANCE.

1,381,305.

Specification of Letters Patent. Patented June 14, 1921.

Application filed August 27, 1917. Serial No. 188,409.

To all whom it may concern:

Be it known that I, HARRY J. HICK, a citizen of the United States, residing at Alliance, in the county of Stark and State of Ohio, have invented certain new and useful Improvements in Filing Appliances, of which the following is a specification.

The invention relates to a filing appliance for physicians' and surgeons' records in which a plurality of upright holding frames or leaves are pivotally mounted upon a supporting frame or table for swinging their free ends apart for giving access to the filing faces of the holders.

15 In records of this kind, it is customary to use a form card containing suitable blanks for the history and diagnosis of a case, together with the name and status of the account of the patient; and the latter information is preferably carried at the extreme top of the card so as to be visible when the hinged holders are inclined rearward in echelon arrangement with respect to the supporting table, but will not be readily visible 25 when positioned perpendicular thereto.

The object of the present invention is to provide an appliance of this character in which the supporting table or frame can be readily tilted from a horizontal to an inclined position and at the same time the hinged holders will automatically swing from a perpendicular to an upright echelon arrangement, with reference to the supporting table; with means for temporarily stopping or locking the frame and holders in the latter position.

These objects of the invention and other ancillary advantages are attained by the construction, mechanism and arrangement, illustrated in the accompanying drawings, forming part hereof, in which—

Figure 1 is a front elevation of a roll top desk or stand partly broken away, with the filing appliance mounted thereon;

45 Fig. 2, a side elevation of the same with the roll top and filing appliance in section, as on line 2—2, Fig. 1, showing the roll top closed and the tilting frame in horizontal position with the hinged holders substantially perpendicular thereto;

50 Fig. 3, a front elevation of the desk with the roll top open showing the filing appliance tilted to bring the holders in operative echelon arrangement;

Fig. 4, a section of the same on line 4—4, 55
Fig. 3;

Fig. 5, a fragmentary perspective view showing the method of mounting one holder upon the tilting frame;

Fig. 6, a fragmentary perspective view 60 showing the filing face on one holder; and

Fig. 7, a face view of a record card.

Similar numerals refer to similar parts throughout the drawings.

The desk or table may be of any design 65 or form and preferably comprises the legs 1, the drawers 2, the table 3, the top 4 and the roll curtain 5; which latter may constitute a closed receptacle for the tilting frame 6 and the record holders 7 when in normal inoperative position as shown in Fig. 2, the operation of the curtain closure being independent 70 of the operation of the tilting frame and the record holders.

The tilting frame 6 is preferably made of 75 two longitudinal angle bars 8 along each side with a connecting plate 9 forming the body or bottom of the frame. The upturned flange of each channel bar is provided with a series of inturned pivot pins 10 which are 80 entered into the ends of the tubular hinge bars 11 formed or secured along the lower edges of the record holders 7.

One or more controlling springs 12 are provided for each holder, and as shown, 85 these springs may be in the form of coils mounted on tongues 13 struck up from the bottom plate of the tilting frame, having one arm 12' extended along the upper side of the bottom plate, and the other arm 12'' 90 extended upward along the rear side of the bill holder with which it may be slidably engaged by means of the L-tongue 12''' operating in the elongated loop 14 struck from the body of the holder, as shown in detail 95 in Fig. 5. The energy of these springs is exerted to rotate the holders backward or rearward upon the tilting frame.

The tilting frame is pivotally mounted by means of the trunnions 15 extending laterally from the outer sides of the angle bars 8, and located slightly forward from the median line of the frame, which trunnions are carried in the bearings 16 formed in the plates 17 secured to the side walls 18 of the 100 top of the desk. A suitable stop 19 is provided for limiting the downward movement of the rear end of the tilting frame, 105

which stop, as shown, may be in the form of blocks secured to the side walls of the desk under the rear end of the tilting frame.

The suitable abutment rollers 20 are pivotally mounted, one at the upper rear end of each side wall of the desk, against which rollers the side edges of the rear holder are adapted to operate for limiting the rearward rotation thereof, as shown in Figs. 2 and 4. A triangular bracket 21 is formed or secured on the back at each side of the rear holder 7', the longer side of which bracket is inclined downward and rearward, and the shorter side thereof is substantially perpendicular to the holder, thus forming stops adapted to be engaged by the abutment rollers 20, for holding the rear end of the tilting frame upward with the holders in operative position, as shown in Fig. 4.

It will be understood that the roll curtain 5 of the desk is first opened and when the tilting frame is swung upward from the inoperative position shown in Fig. 2, to the operative position shown in Fig. 4, the abutment rollers will ride upon the inclined face of the triangular bracket until they can pass under the shoulder formed by the perpendicular face thereof, which should rotate rearward upon the abutment roller by the combined action of the controlling springs of all the holders tending to move them rearward, which position of the parts is shown in Fig. 4; and in this position the forward end of the tilting frame preferably impinges the bottom 22 of the desk top.

In this operative relation of the parts, the tilting frame may be inclined upward and rearward at an angle of about 25 or 30° from a horizontal plane, and the action of the controlling springs holds all the leaves in an upright echelon arrangement, at a rearward inclination with reference to the tilting frame, so that the upper end of each holder is slightly exposed above the upper end of the next forward holder, thus displaying the name and amount contained at the top of each record card carried by the holder, as shown in Fig. 3.

In order to read the remainder of the record contained in a particular card, or to remove the same from behind the spring clip 23 by which they are held upon the face of the holder, it is only necessary for the operator to grasp the upper end of the next forward holder, and by pulling the same forward, the filing face of the particular holder is exposed to view and rendered accessible for the entrance or withdrawal of record cards.

For returning the appliance to the normal inoperative position shown in Fig. 2, it is only necessary to grasp the rearmost holder and pull it forward against the action of the controlling springs far enough to disengage the stop shoulders formed by the

triangular brackets from the abutment rollers, whereupon the tilting frame may be freely rotated into horizontal position, in which position it is stopped by the combined action of the block 19 at the rear end, and the abutment rollers 20 against the rear holder of the series after which the roll curtain 5 may be closed as shown in Fig. 2.

It is obvious that the filing appliance proper, composed of the tilting frame and pivotal holders are adapted to be readily removed from the desk, as for filing in a fire-proof vault, by merely lifting the pivotal trunnions from their supporting bearings, and that removed from the desk, the abutment of the L-bend 12" on the end of the spring arm 12" against the upper end of the loops 14, serves to stop the rearward rotation of the holders with respect to the supporting frame, and it is evident that the location of the pivotal support slightly forward of the median line of the tilting frame, so nearly counterbalances the end portions thereof that the frame may be readily tilted *in situ* by a slight pressure applied to the stops of the forward holders thereon; and also that when the tops on the rearmost holder are disengaged from the abutment rollers the tilting frame will resume its normal horizontal position without injuriously impinging the rear top at the rear end thereof.

I claim:

1. A filing appliance including a normally horizontal frame pivotally mounted on a transverse axis slightly forward from the median line thereof, and a plurality of normally upright holders pivoted on the frame in rectangular arrangement and adapted to be rotated into an echelon arrangement by a tilting of the frame on its axis.

2. A filing appliance including a normally horizontal frame pivotally mounted on a transverse axis slightly forward from the median line thereof, a plurality of normally upright holders pivoted on the frame in rectangular arrangement, and means tending to rotate the holders rearward whereby they are swung into an echelon arrangement by a tilting of the frame on its axis.

3. A filing appliance including a normally horizontal frame, pivotally mounted on a transverse axis slightly forward from the median line thereof, a plurality of holders pivoted on the frame, means normally stopping the holders in upright position, and means tending to rotate the holders rearward whereby they are swung into an echelon arrangement by a tilting of the frame on its axis.

4. A filing appliance including a normally horizontal frame pivotally mounted on a transverse axis slightly forward from the median line thereof, a plurality of normally upright holders pivoted on the frame, means

normally stopping the holders in rectangular arrangement, means for rotating the holders rearward, in echelon arrangement when the frame is tilted, and means for stopping the frame and holders in tilted echelon arrangement.

5. A filing appliance including a normally horizontal frame, a plurality of normally upright holders pivoted on the frame in rectangular arrangement, springs acting to rotate the holders rearward, an abutment for the rear end holder resisting the action of the springs, and means permitting the frame to tilt on a transverse axis slightly forward 10 from the median line thereof, whereby the holders rotate into rearwardly inclined echelon arrangement with reference to the tilted frame.

6. A filing appliance including a normally horizontal frame, a plurality of normally upright holders pivoted on the frame in rectangular arrangement, springs acting to rotate the holders rearwardly, an abutment for the rear end holder resisting the action 15 of the springs, means permitting the frame to tilt on a transverse axis slightly forward of its median line whereby the holders rotate into rearwardly inclined echelon arrangement with reference to the frame, and 20 a stop on the rear end holder for engaging the abutment and holding the frame and holders in tilted echelon arrangement.

7. A filing appliance including a normally horizontal frame, a plurality of normally upright holders pivoted on the frame in rec- 25

tangular arrangement, springs acting to rotate the holders rearwardly, an abutment for the rear end holder resisting the action of the springs, means permitting the frame to tilt on a transverse axis slightly forward of 40 its median line whereby the holders rotate into rearwardly inclined echelon arrangement with reference to the frame, and a stop on the rear end holder for automatically engaging the abutment and holding the frame 45 and holders in tilted echelon arrangement.

8. A filing appliance including a supporting frame, a plurality of upright holders normally held in rectangular arrangement thereon, a plurality of cards carried by the 50 holders having account records or the like at their upper ends normally concealed by the holders, and means for tilting the frame *in situ* to move the holders into upright echelon arrangement for exposing the account 55 records.

9. A filing appliance including a case, a supporting frame mounted thereon, a plurality of upright holders on the frame normally held in rectangular arrangement, a 60 plurality of cards carried by the holders having account records or the like at their upper ends normally concealed by the holders, a closure for the case operable independently of the holders, and means independent of the closure for tilting the frame 65 *in situ* to move the holders into upright echelon arrangement for exposing the account records.

HARRY JOSEPH HICK.
